INVENTOR.

JOHN C. SMITH

BY

Watson E. Coleman

ATTORNEY.

UNITED STATES PATENT OFFICE.

JOHN C. SMITH, OF JERSEY SHORE, PENNSYLVANIA.

WRENCH.

1,386,905.

Specification of Letters Patent.

Patented Aug. 9, 1921.

Application filed March 9, 1921. Serial No. 450,890.

To all whom it may concern:

Be it known that I, JOHN C. SMITH, a citizen of the United States, residing at Jersey Shore, in the county of Lycoming and State of Pennsylvania, have invented 5 certain new and useful Improvements in Wrenches, of which the following is a specification, reference being had to the accompanying drawings.

10 This invention relates to improvements in wrenches and more particularly to a quick adjustable monkey wrench.

An important object of the invention is to 15 provide a device of this character which may be readily shifted to adjusted positions and in which the movable jaw may be locked in position either for movement or against movement, as may be desired.

20 A further object of the invention is to provide a wrench of this character embodying the usual shank and fixed jaw and having a yoke slidably mounted upon the shank and held against transverse movement with 25 relation thereto, the yoke coacting with a wedge-shaped movable jaw to clamp the same to the shank.

A further object of the invention is to 30 provide a device of the above mentioned character in which the movable jaw may be locked in the yoke either in engagement with the shank or in spaced relation thereto.

Other objects and advantages of the invention will become apparent throughout the following description.

35 In the accompanying drawings wherein for the purpose of illustration is shown a preferred embodiment of my invention, and wherein like reference characters designate like parts throughout,

40 Figure 1 is a side elevation of a wrench constructed in accordance with my invention showing the yoke and movable jaw in the position in which they are locked against movement with relation to the shank of the 45 wrench;

Fig. 2 is a similar view showing the yoke shifted to permit of movement of the movable jaw and yoke upon the shank;

Fig. 3 is a section on the line 3—3 of Fig. 50 1, and

Fig. 4 is a sectional view partially in elevation taken through the yoke and movable jaw removed.

Referring now more particularly to the 55 drawings, the numeral 10 indicates a shank provided at one end with the usual handle

member 11, and at the other end with a fixed jaw 12 of the type usually employed in monkey wrenches. The shank 10 is provided in the side faces thereof with grooves 13, and an edge face of the shank, more particularly that edge face underlying the jaw 12, is corrugated as indicated at 14.

The numeral 15 indicates a movable jaw which is wedge-shaped, being tapered longitudinally. In the side faces of the movable jaw 15, grooves 16 are provided and the inner edge of the movable jaw, or that edge coacting with the corrugated edge of the shank 10, is corrugated as indicated at 17. 70 The grooves of the movable jaw 15 are parallel to the inclined tapered face thereof.

The numeral 18 designates a yoke slidably mounted upon the shank 10 and held against transverse movement with relation thereto 75 by means of ribs 19 formed upon the interior of the yoke and engaged in the grooves 13 of the side faces of the shank. The outer face of the yoke 18 is inclined to correspond to the inclination of the outer face of the 80 movable jaw 15, and the yoke is provided interiorly with inclined ribs 20 engaging in the grooves 16 of these movable jaws. It will be obvious that if the movable jaw 15 is held stationary and the yoke 18 is shifted 85 upon the shank 10, the movable jaw will be moved toward or away from the shank dependent upon the direction of movement of the yoke, the movement being toward the shank when the yoke is moved toward the 90 fixed jaw 12, and being away from the shank when the yoke is moved toward the handle 11.

When the yoke is moved toward the jaw 12 sufficiently to cause the corrugated face 95 17 of the movable jaw to firmly engage the corrugated face 14 of the shank 10, it will be obvious that the movable jaw and yoke are both held against further movement. In order to prevent accidental slipping of the 100 yoke upon the shank and movable jaw, I form upon the outer face of the yoke, spaced ears 21 to which a lever 22 is pivoted intermediate its ends. This lever has at one end a down-turned portion 23 extending through 105 an opening 24 formed in the yoke and engaging in a notch 25 formed in the movable jaw 15, when the yoke and jaw are in the position above described. A spring disposed beneath the other end of the lever 22, as at 110 26, normally forces the end 23 inwardly for this engagement. When it is desired to

shift the movable jaw the lever is depressed to free the end 23 from the notch 25 and the yoke shifted toward the handle 11, the groove and rib engagement of the yoke with 5 the movable jaw causing the movable jaw to shift outwardly until it is free from engagement with the shank. At this time the tongue or end 23 of the lever 22 is alined with a second notch 27 formed in the movable jaw and will engage therewith so as to prevent relative shifting of the yoke and movable jaw, so that the yoke and jaw may be adjusted to any desired position. When 10 the desired adjustment has been made the wrench may be locked as above described.

From the foregoing it is believed to be obvious that I have constructed a wrench which is particularly well adapted for the use for which it is intended by reason of 20 the fact that it provides for a very quick adjustment of the movable jaw, and by reason of the fact that the wrench may readily be locked in adjusted position, and it will furthermore be obvious that the construction 25 of the same as hereinbefore set forth is capable of some modification without departing from the spirit of my invention. I accordingly do not limit myself to specific structure hereinbefore set forth except as 30 hereinafter claimed.

What I claim is:

1. In a wrench, a shank embodying a fixed jaw, a yoke slidably mounted on the shank and held against transverse shifting with relation thereto, a movable jaw longitudinally shiftably mounted in the yoke, and a connection between the yoke and movable jaw whereby said movable jaw is shifted transversely upon relative shifting movement of 35 the yoke and movable jaw.
2. In a wrench, a shank embodying a fixed jaw, a yoke slidably mounted on the shank and held against transverse shifting with relation thereto, a movable jaw longitudinally shiftably mounted in the yoke, said shank and movable jaw being provided with coacting roughened faces, and a connection between the yoke and movable jaw whereby said movable jaw is shifted trans- 45 versely upon relative shifting movement of the yoke and movable jaw to move the

roughened face thereof into or out of engagement with the roughened face of said shank.

3. In a wrench, a shank embodying a fixed 55 jaw, a yoke slidably mounted on the shank and held against transverse shifting with relation thereto, a movable jaw longitudinally shiftably mounted in the yoke, said shank and movable jaw being provided with coacting roughened faces, a connection between the yoke and movable jaw whereby said movable jaw is shifted transversely upon relative shifting movement of the yoke and movable jaw to move the roughened face 60 thereof into or out of engagement with the roughened face of said shank, and means for locking said yoke and shiftable jaw against relative shifting movement.

4. In a wrench, a shank embodying a 70 fixed jaw provided in the side faces thereof with longitudinally extending grooves, a yoke slidably mounted upon the shank and embodying portions engaging in said grooves and holding said yoke against transverse 75 shifting upon the shank, a tapered movable jaw longitudinally shiftably mounted in the yoke and provided in the side faces thereof with grooves paralleling its tapered face, said yoke likewise embodying portions extending into the grooves of said movable jaw, said shank and movable jaw being provided with coacting corrugated faces.

5. In a wrench, a shank embodying a 85 fixed jaw provided in the side faces thereof with longitudinally extending grooves, a yoke slidably mounted upon the shank and embodying portions engaging in said grooves and holding said yoke against trans- 90 verse shifting upon the shank, a tapered movable jaw longitudinally shiftably mounted in the yoke and provided in the side faces thereof with grooves paralleling its tapered face, said yoke likewise embodying portions extending into the grooves of said movable 95 jaw, said shank and movable jaw being provided with coacting corrugated faces, and means for locking said yoke and shiftable jaw against relative shifting movement.

In testimony whereof I hereunto affix my 100 signature.

JOHN C. SMITH
